ATTORNEY

UNITED STATES PATENT OFFICE.

GEORGE W. CONLEY, OF WHEATON, ILLINOIS.

BELT-BUCKLE.

1,268,326.

Specification of Letters Patent.

Patented June 4, 1918.

Application filed May 26, 1917. Serial No. 171,272.

To all whom it may concern:

Be it known that I, GEORGE W. CONLEY, a citizen of the United States, residing at Wheaton, in the county of DuPage and 5 State of Illinois, have invented certain new and useful Improvements in Belt-Buckles, of which the following is a specification.

This invention relates to new and useful improvements in belt buckles and the principal object of the invention is to provide clamping means to replace the tongue now in use.

Another object of the invention is to provide means whereby the pressure of the 15 body of the wearer tends to increase the clamping action.

A further object of the invention is to provide locking means for holding the two parts of the clamping means together with 20 the belt gripped between them.

Another object of the invention is to provide a device of this character, which is simple and durable in construction, reliable and efficient in operation and one which can 25 be manufactured and placed upon the market at a minimum cost.

The invention also consists in certain other features of construction and in the combination and arrangement of the several parts, to be hereinafter fully described, 30 illustrated in the accompanying drawings and specifically pointed out in the appended claims.

In describing my invention in detail, reference will be had to the accompanying drawings, wherein like characters denote 35 like or corresponding parts throughout the several views, and in which:

Figure 1 is a front view of the invention. 40 Fig. 2 is an edge view thereof.

In these figures 1 represents the main or lower plate of the buckle, provided with a loop 2 at one end to which one end of the belt 3 is secured. 4 represents the upper plate, and these plates are provided with holes 5 through which a pair of links 6 and 7 are passed, the link 6 connecting the plates together at one end while the link 7 connects the plates together at the other end.

50 The links are made of sufficient width so that when the plates are moved apart the free end 8 of the belt may pass between the plates. The plate 1 is of greater length than the plate 4 and at its free end said 55 plate is provided with a spring catch 9 projecting upwardly from the face of the plate

and adapted to engage with the end edge of the plate 4 to hold said plate in its lowermost position. A second catch 10 pivoted to the edge of the plate 1 as at 11 is adapted to be swung over in engagement with the face of the plate 4 to prevent said plate from being moved away from the plate 1. The opposing faces of the two plates are preferably provided with corrugations 12. 60

The link 7 is provided with extensions 13 which extend beyond the free end of the buckle, where they are provided with a loop 14 through which the belt is passed before being passed through the buckle. 70

When the belt is to be used the catches 9 and 10 are swung out of engagement with the plate 4 so as to permit said plate to be swung away from the plate 1. In this position of the plates the links 6 and 7 are at 75 right angles with the plates and the loop 14 is moved inwardly beyond the lower face of the plate 1. In applying the belt, after the same is passed around the body the end 8 is passed through the loop 14 and between 80 the plates 1 and 4, and then the belt is tightened. This action will cause the loop 14 to be pressed away from the body and through its connection with the link 7 will cause the plate 4 to swing toward the plate 85 1, thus gripping the belt between the plates, after which the catches 9 and 10 are swung into engagement with the plate 4 to hold said plate in contact with the belt. The pressure of the body against the loop 14 90 tends to hold the plates in gripping contact with the belt, though I prefer to use the catches to insure that the plates remain in contact with the belt.

It is thought from the foregoing that the 95 advantages and novel features of my invention will be readily apparent.

I desire it to be understood that I may make slight changes in the construction and in the combination and arrangement of 100 the several parts, provided that such changes fall within the scope of the appended claims.

I claim as my invention:

1. A belt buckle comprising a pair of 105 superposed plates having teeth on their opposed faces for biting engagement with the belt, links connecting said plates, one of said links having an extension projecting beyond the inner plate and adapted to be 110 engaged by the body of the wearer to hold said plates united, said links being posi-

tioned at oblique angles to the plates when in operative position.

2. A belt buckle comprising a pair of superposed plates, one of said plates being longer than the other, coöperating elements on the inner faces of said plates for engagement with the belt to be secured, links connecting said plates, and a fastener mounted on the longer plate at one end thereof and positioned to engage the shorter plate to hold it against longitudinal movement when in operative position.

3. A belt buckle comprising a pair of superposed plates, links connecting said plates and adapted to be obliquely disposed

relatively thereto when in closed operative position and to extend at right angles when in inoperative position, one of said plates being longer than the other, a catch pivoted at one end on the longer plate and having 20 its free end adapted to engage the shorter plate when in operative position to hold said plates against longitudinal movement relatively to each other.

In testimony whereof I affix my signature 25 in presence of two witnesses.

GEORGE W. CONLEY.
